PADLOCK

Ernest L. Schlage, Burlingame, Calif., assignor to
SCHLAGE LOCK COMPANY, a corporation

Application December 3, 1951, Serial No. 259,630

6 Claims. (Cl. 70—38)

1

My invention relates to locks for use in connection with a shackle movable with respect to the lock body both in rotation and in translation and controlled largely by a lock unit preferably of the pin-tumbler type.

It is an object of my invention to provide an improved padlock.

Another object of my invention is to provide a padlock which is readily assembled and disassembled when it is in open condition but which is very difficult of access when it is in closed condition.

A still further object of my invention is to provide a padlock in which the positioning and retention of the various interior parts is accomplished in a superior fashion.

Another object of my invention is to provide a padlock which is comprised of parts readily manufactured and of a sturdy and long lived construction.

Other objects, together with the foregoing, are attained in the embodiment of the invention described in the accompanying description and illustrated in the accompanying drawings, in which

Figure 1 is a cross section for the most part on a transverse plane through a padlock of my invention in locked position or condition.

Figure 2 is a view similar to Figure 1 but showing the padlock in unlocked condition.

Figure 3 is a cross section, the plane of which is indicated by the line 3—3 of Figure 1.

Figure 4 is a cross section, the plane of which is indicated by the line 4—4 of Figure 2.

Figure 5 is a fragmentary cross section, the plane of which is indicated by the line 5—5 of Figure 1.

Figure 6 is a fragmentary view showing the split shell in plan and in expanded condition with the bolt in transverse cross section.

Figure 7 is a cross section through the bolt.

Figure 8 is a cross sectional view to an enlarged scale showing the bolt of Figure 7 in position in the lock body.

Figure 9 is a side elevation of the plug.

Figure 10 is an end view of the plug as shown in Figure 9.

The padlock of my invention is susceptible of embodiment in a number of different forms depending upon its special use and the environment in which it is to operate, and it has successfully been incorporated in the form shown herein which includes a lock body generally designated 6. This is primarily a solid block of metal fabricated or machined to provide a pair of parallel

2

recesses 7 and 8 which enter the body from the upper face 9 thereof and is likewise provided with a pair of parallel bores 11 and 12 which enter the body from the lower face 13 thereof. The position of one of the bores 11 is such that it intersects the recess 7 in an offset fashion to provide an intervening wall 14 therebetween. The recess 7 is also provided with an interiorly enlarged chamber 16 formed by an undercut portion. Somewhat similarly, the bore 11 is provided with an interiorly enlarged chamber 17 formed by an undercut portion.

Slidably disposed within the recess 8 is the long leg 21 of a shackle 22 also having a short leg 23. The long leg 21 is generally circular cylindrical in cross section, yet at its lower end is provided with a planar flat face 24 merging with a circumferential groove 26 to leave a flange 27 on the shackle. A coil spring 28 is disposed within the recess 8, at one end bears on the body 6 at the bottom of the recess and at the other end bears against the lower face of flange 27. Thus the spring normally tends to urge the shackle 22 out of the body 6.

The extent of outward movement of the shackle is limited by a plug 29 formed, especially as shown in Figures 9 and 10, of stock circular cylindrical in cross section yet cut away to provide a lip 31. The plug 29 is situated in an inclined passageway 32 formed in the body 6 and opening into the bore 12 and also into the recess 8. The plug 29 is introduced through the empty bore 12 to occupy a position with the lip 31 in the path of the flange 27 to limit the outward movement of the shackle. Since the edge of the lip 31 fits against the surface 24, rotation of the shackle 22 is precluded except when the shackle is in its extreme outermost position in which instance the lip 31 rides in the groove 26. The plug 29 is easily assembled after the shackle 22 has been positioned in the body and is held against dislodgment by a light staking of the material of the body at the lower end of the plug.

To secure the shackle 22 in its closed position with the short leg 23 received in the recess 7, the body is provided with a cross bore 36 in which a pair of pawls 37 and 38 are translatable. The pawls are each provided with circular cylindrical bodies readily movable within the cross bore and are normally spread apart by pawl springs 39 and 41 guided by the walls of cavities 42 in the individual pawls and by pins 43 for the exposed portion of the springs. The pawls are readily assembled by introduction into the bore 36. After that the bore is closed by a seal 44, primarily a hard-

ened plug. This is driven into the relatively softer material of the body and, being somewhat oversized and being grooved to form a sharp cutting edge 46, is effective when it is driven into position to broach the interior metal of the bore 36. This provides an inturned lip interengaging with the groove to hold the seal in position against dislodgment. The metal of the seal and of the lock body are finished flush and when brushed or polished cannot be visibly detected from the outside.

To actuate the pawls 37 and 38, each of them is provided with a projection 48 and 49 disposed on opposite sides of a tongue 51 rotatably projecting from the end of a lock unit 52 located within the bore 12. When the lock unit is actuated by an appropriate key 53, the tongue 51 is turned and abuts the depending portions 48 and 49 to slide the pawls within the bore 36 with respect to each other and to compress the springs 39 and 41. The pawls themselves are then withdrawn from their spring pressed positions within notches 54 and 56 respectively provided in the facing portions of the shackle legs 21 and 23. When the key 53 is released, the springs 39 and 41 are effective to project the two pawls into interengagement with the shackle 22.

The lock unit 52 is positioned within the body through the medium of a split shell 57, especially illustrated in Figures 5 and 6. This is provided with a side slot 58 to receive a fin 59 projecting from the otherwise circular cylindrical body of the lock 52. The fin is disposed in the slot 58 and is retained by the bottom 61 of the shell. The shell itself has a substantially circular cylindrical envelope for much of its dimension, receivable within the bore 11. The shell is particularly formed so that the slot 58 not only extends through one side thereof but is continued to provide a transverse slot 62 entirely across the upper wall 63 of the shell. The upper wall is extended to afford a beveled outwardly projecting, interrupted circumferential flange 64 and when relaxed of an outer diameter readily slid able through the bore 11. The location of the flange 64 is such that when the shell 57 together with the lock unit 52 are positioned in the bores 11 and 12 in the body 6, the flange 64 registers with the undercut portion and occupies much of the chamber 17 so provided.

In order to hold the lock unit and the split shell in position as assembled within the body, there is provided a special bolt 66 as shown in Figures 7 and 8. The bolt is provided with the customary threaded shank 67 and has the usual screw driver slot 68 in its head 69. In addition, however, the special bolt has a deformable skirt 71 surrounding its head and when first constructed extending outwardly and downwardly to form an abutment ring 72. The diameter of the skirt 71 is sufficiently small so that the bolt can pass through the recess 7 without difficulty.

When the parts are assembled, the bolt is introduced into the recess 7 and the threaded shank 67 passes through the communication between the recess 7 and the bore 11 and engages the threaded walls 73 of a bore in the split shell 57. The upper entry of the bore 73 is conical so that the bolt 66 enters readily but as it is turned and threaded more and more into the aperture 73 it widens the gap 62 and spreads the split shell laterally apart. The material of the shell itself is somewhat deformable or resilient so that when the bolt is fully engaged, the flange 64 is spread

outwardly into the recess 16 so that the shell cannot be withdrawn while the bolt is present.

Alternatively, by slightly changing the proportions of the split shell 57, the split shell can be made of a size to pass readily into the bore 11 and to have the parts of the flange 64 spring outwardly into the chamber 17 so that no further expansion is necessary. In this instance, the shank 67 of the screw does not distort the split shell but merely prevents the shell from collapsing inwardly. In fact, the threaded walls 73 can be tapped oversize for ready assembly and disassembly.

In addition and to keep the bolt 66 from too ready dislodgment, the skirt 71 engages the body 6 of the lock at the bottom of the chamber provided by the undercut recess 16 and as the bolt is screwed in, the skirt 71 is deformed outwardly as shown in Figure 8 until it substantially occupies the undercut chamber and has a diameter in excess of the diameter of the recess 17. The bolt is not only locked in position by this deformation but cannot readily fall out of or be removed from the chamber 16 without again deforming the bolt in a reverse sense.

If the bolt should become partially loosened a serious amount it projects into the path of closure of the short leg 23 and prevents closure of the shackle, thus indicating the disorder.

With this arrangement, when the shackle 22 is in open position all of the structure can be assembled as indicated, but when the shackle 22 is forced into locked position with the pawls 37 and 38 in engagement with the notches 54 and 56, the short leg 23 of the shackle being in the recess 7 overlies the bolt 66 and precludes the use of any tool for the extraction of the bolt. Since the bolt has expanded or retains the shell 57 in position, the shell itself cannot be withdrawn from the bore 11. Since the extension 59 of the lock unit 52 is itself confined within the shell, the lock unit cannot be withdrawn. Furthermore, the lock unit itself is in the path of withdrawal of the plug 29 so that the plug is substantially immovably held in engagement with the long leg 21 of the shackle. In this construction, therefore, the lock is held in assembled condition and cannot readily be tampered with when it is locked. However, when it is unlocked and the short leg 23 is moved from the recess 7, then upon deformation and unscrewing of the bolt 66, the shell 57 and the lock unit 52 can be withdrawn from their several bores and the plug 29 if necessary can be extracted.

What is claimed is:

1. A padlock comprising a body having a pair of parallel recesses therein and having a pair of parallel bores therein, one of said recesses and one of said bores communicating and having undercut portions, a shackle having a short leg receivable in said one recess and having a long leg receivable in the other recess, a shell of resilient material partially split to form two opposed sides and positioned in said one bore, a lock unit receivable in the other bore and having a projection extending into said shell, pawls disposed in said body and engageable with said legs, means operated by said lock unit for actuating said pawls, a bolt in said one recess and threadedly engageable with said split shell for urging said sides away from each other whereby portions of said sides enter one of said undercut portions, and a deformable head on said bolt engageable with said body to spread into the other of said undercut portions.

2. A padlock comprising a body having a recess therein and having a bore therein, said recess and said bore communicating and having undercut portions, a shell of resilient material partially split to form two opposed sides and positioned in said bore, a lock unit having a projection extending into said shell, a bolt in said recess and threadedly engageable with said split shell for urging said sides away from each other whereby portions of said sides enter said undercut portion of said bore, a deformable head on said bolt engageable with said body to spread into said undercut portion of said recess, and a shackle controlled by said lock unit and movable on said body to extend into said recess.

3. A padlock comprising a body having a recess therein and having a bore therein, said recess and said bore communicating and having undercut portions, a shell of resilient material partially split to form two opposed sides and positioned in said bore, a lock unit having a projection extending into said shell, a bolt in said recess and threadedly engageable with said split shell for urging said sides away from each other whereby portions of said sides enter said undercut portion of said bore, and a shackle controlled by said lock unit and movable on said body to extend into said recess.

4. A padlock comprising a body having a bore therein, said bore having an undercut portion, a shell of resilient material partially split to form two opposed sides and positioned in said bore, a lock unit having a projection extending into said shell, a bolt threadedly engageable with said split shell for urging said sides away from each other whereby portions of said sides enter said undercut portion, and means controlled by said lock unit and movable on said body to overlie said bolt.

5. In a lock mounting device for use with a padlock having a body formed with a recess in one side thereof and adapted to receive one end of a shackle therein and a lock socket on the other side of said body for receiving a lock, said device comprising: a tubular cylindrical shell adapted to be received in a complementarily formed bore opening outwardly of said other side of said body and communicating with said socket, a bolt threadedly received in one end of said shell and engageable with the bottom of said recess for holding said shell in said body, said shell

being partially split from said one end axially of the same to form a pair of opposed sides separated by a pair of radially outwardly opening slots with one of said slots adapted to receive therethrough the combination extension of a lock in said lock socket, said sides being deformable whereby turning said bolt into said shell will spread said sides apart into engagement with the sides of said bore.

10 6. In a lock mounting device for use with a padlock having a body formed with a recess in one side thereof and adapted to receive one end of a shackle therein and a lock socket on the other side of said body for receiving a lock, said device comprising: a tubular cylindrical shell adapted to be received in a complementarily formed bore opening outwardly of said other side of said body and communicating with said socket, a bolt threadedly received in one end of said shell and engageable with the bottom of said recess for holding said shell in said body, said shell being partially split from said one end axially of the same to form a pair of opposed sides separated by a pair of radially outwardly opening slots with one of said slots adapted to receive therethrough the combination extension of a lock in said lock socket, said sides being deformable whereby turning said bolt into said shell will spread said sides apart into engagement with the sides of said bore.
